UNITED STATES PATENT OFFICE.

ROBERT E. DUKE, OF WHITE SULPHUR SPRINGS, WEST VIRGINIA.

RAIL-JOINT.

1,278,611.

Specification of Letters Patent. Patented Sept. 10, 1918.

Application filed November 15, 1916. Serial No. 131,601.

To all whom it may concern:

Be it known that I, ROBERT E. DUKE, a citizen of the United States, residing at White Sulphur Springs, in the county of Greenbrier and State of West Virginia, have invented certain new and useful Improvements in Rail-Joints, of which the following is a specification.

This invention relates to an improvement 10 in rail joints, and has for its object to provide an improved fish plate to be applied one to each side of a rail joint and bolted thereto for holding the ends of the rails in alinement.

15 Another object of the invention is to provide a fish plate for rail joints two of which are to be used in coöperation to form a strong and secure means for holding the rails in alinement and for supporting the terminals 20 of the rails to prevent depression thereof by the passing of trains thereover.

A further object of the invention is to provide a fish plate which shall be strong, relatively light and which will withstand the 25 severe strains to which it is subjected by the passing of heavy trains along the rails.

With these as the principal objects in view, the invention consists in the construction, combination, and arrangement of parts 30 hereinafter described, pointed out in the appended claim and illustrated in the accompanying drawings, in which:

Figure 1 is a side elevation of the joint between two rails connected together by the 35 improved fish plate of the present invention;

Fig. 2 is a vertical transverse sectional view of the same on the line 2—2 of Fig. 1; and

Fig. 3 is a similar view on the line 3—3 40 of Fig. 1.

In the drawing, A indicates the end of one rail and B indicates the end of another rail joined together endwise as is usual in laying railroad tracks. The two rails are 45 connected together by fish plates 10, one on each side of the track through which plates and through the web of the rails are passed bolts 11 by means of which the several parts forming the rail joint are connected together.

Each fish plate 10 comprises a central horizontal portion 12 that extends longi-

tudinally of the track and is substantially triangular in cross section, see Fig. 3. The central portion 12 of each fish plate is placed 55 against the web of the rails opposite the joint between them and extends from the base flange of said rails upwardly but not quite to the shoulder below the head of the rails. The base of each body portion 12 extends outwardly beyond the edge of the base flange of the rails and then below the same to the center line thereof, each fish plate by this means being provided with a broad foot piece or plate 13, one of them terminating 60 with a flange 14 and the other a groove 15 into which the flange 14 fits snugly when the fish plates are assembled in place. The horizontal portion 12 of each fish plate is made of any desired or suitable length, the plates 70 13 being substantially as long as said portion which length is sufficient to give a firm support to the meeting ends of the rails A and B and prevent sagging of said ends due to the weight of passing trains. The ends 75 of each fish plate incline upwardly at a slight angle in opposite directions as at 16 until they bear against the under side of the head of the rail at 17, the extreme ends of the inclined portions 16 projecting downwardly at 18 to the base flange and extend over the top thereof to the outer edge. Through each inclined portion 16 is formed two holes for the bolts 11 and a single hole 80 in each part 18 also for one of the fastening bolts, bosses being formed as at 19 around each hole to give a square and true seating to the bolt heads 20 and nuts 21.

Each fish plate as thus constructed forms a truss to support the ends of the rails A 90 and B, each end of each fish plate being firmly secured to the rail between the base flange and the under side of the head while the intermediate portion 12 of the fish plate extends below the rail at the joint and forms 95 a supporting means therefor.

What is claimed is:

A rail joint comprising two fish plates, each of said plates being of inverted arch formation and of triangle cross section, the 100 centers of which plates are supported on the flanges of the connected rails at the abutting ends thereof while the ends of the fish plates bear against the undersides of the rail heads,

the vertical dimensions of said plates being less than the distance between the heads and the flanges of the rails, a depending portion on each end of each plate resting on the 5 flanges of the rails, a foot piece extending from the center of each plate under the base of the rail, said foot pieces interlocking at their ends, bosses on the inclined outer sides of the fish plates, and securing bolts for fas-

tening the fish plates to the rails passing 10 through said parts and the bosses.

In testimony whereof I affix my signature in presence of two witnesses.

ROBERT E. DUKE.
